COMBINED SWITCH AND ACOUSTICAL COUPLER

John P. Kennedy, Columbus, Ohio, assignor to
Design Elements, Inc.

Filed Jan. 3, 1972, Ser. No. 215,287

Term of patent 14 years

Int. Cl. D14—03

U.S. Cl. D26—14 A

FIG. 3

FIG. 1

FIG. 4

FIG. 5

FIG. 2

FIG. 1 is a partial cross sectional view of a combined switch and acoustical coupler taken on line 1—1 of FIG. 2;

FIG. 2 is a top plan view;

FIG. 3 is a side elevation of the combined switch and acoustical coupler in its working environment;

FIG. 4 is a top plan view of the switch; and

FIG. 5 is a side elevation thereof.

The broken lines are shown for illustrative purposes only.

I claim:

The ornamental design for a combined switch and acoustical coupler, as shown and described.
